CLAIM

The ornamental design for goggles, as shown and described.

DESCRIPTION

FIG. 1 is a front, top, right perspective view of goggles showing our new design;
FIG. 2 is a front view thereof;
FIG. 3 is a rear view thereof;
FIG. 4 is a left side view thereof;
FIG. 5 is a right side view thereof;
FIG. 6 is a top plan view thereof;
FIG. 7 is a bottom plan view thereof;
FIG. 8 is a rear, top, left perspective view thereof; and,
FIG. 9 is a front, bottom, left perspective view thereof.
The broken lines shown in figures depict portions of the goggles that form no part of the claimed design.

1 Claim, 9 Drawing Sheets
